CLAIM

The ornamental design for an air conditioner outdoor roof unit as shown and described.

DESCRIPTION

FIG. 1 is an upper back perspective an air conditioner outdoor roof unit showing our new design;

FIG. 2 is an upper front perspective thereof;

FIG. 3 is a left-side perspective view of thereof;

FIG. 4 is a right-side perspective view thereof;

FIG. 5 is a top view thereof;

FIG. 6 is a back view thereof; and,

FIG. 7 is a front view thereof.

The bottom view is not shown in a drawing as it forms no part of the claimed design because it is hidden after installation.

1 Claim, 7 Drawing Sheets
